UNITED STATES PATENT OFFICE.

JAMES TIMMS, OF COLUMBUS, OHIO.

CAR-COUPING.

No. 906,170.

Specification of Letters Patent.

Patented Dec. 8, 1908.

Application filed February 8, 1908. Serial No. 413,966.

To all whom it may concern:

Be it known that I, JAMES TIMMS, a citizen of the United States, residing at Columbus, in the county of Franklin and State of Ohio, have invented certain new and useful Improvements in Car-Couplings, of which the following is a specification.

My invention relates to improvements in car couplings, especially in those of the well known Janney type, and comprises improved operating mechanism for manipulating the lock and opening the knuckle.

It consists further in the provision of operating levers so constructed and arranged that the knuckle may be both unlocked and thrown open by a movement of the operating levers in one direction; in devices hitherto constructed for the purpose of operating the knuckle of an automatic coupler, it has been usual to provide a bar or rod, which was required to be moved in one direction for bringing the locking pin to lock-set position and then moved in the opposite direction for pushing the knuckle open, but the purpose of my improvements is to both unlock the knuckle and push it open by the movement of the actuating means in one direction only.

A further object of my improvements is to simplify and cheapen the construction, and to avoid the use of hangers, chains and other accessories generally employed with the operating mechanism now in common use.

With these and other objects in view which will be hereinafter specifically set forth and claimed, reference is made to the accompanying drawings which are hereto attached and hereby made a part of this specification, in which

Figure 1 is a vertical cross section showing my improvements applied to a coupling head, the knuckle being in locked position; Fig. 2 is a vertical cross section showing the parts operated and the knuckle in open position; Fig. 3 is an upper plan view showing the knuckle and the operating parts in both open and closed position; Fig. 4 is a view of the levers disconnected from the coupling head and from each other. Fig. 5 is a modification of lever 12, the hook portion being formed integral with the lever.

In the drawings, 1 is the coupling head, having a vertical opening 2 therethrough, in which is positioned a locking pin 3 adapted to move upwardly and downwardly therein; 4 is the tail of a pivoted or swinging knuckle

adapted to be locked by the locking pin 3; adjacent its lower end the locking pin contains the shoulder 5, which when the pin is in its raised position, as seen in Fig. 2, rests upon the ledge 6 formed in the coupling head, and thereby the pin 3 is supported in its lock-set position. When the locking pin is in this position, the knuckle tail is unlocked and is free to swing through the recessed portion 7 of the locking pin.

My improvements have for their chief object the means for lifting the locking pin 3 to its lock-set position and swinging the knuckle completely open, and I accomplish these results as follows: Fulcrumed at 8 upon the outer face of the locking head 1 is a bell crank lever 9 having one end formed with the cam face 10 to engage the bevel face 11 formed at the lower end of locking pin 3, whereby when the lever 9 is swung outwardly, the engagement of faces 10 and 11 not only lifts the locking pin, but also moves it to one side so that the shoulder 5 is made to engage with and rest upon the ledge 6; adjacent its other end the lever 9 is constructed to receive the lever 12 which is fulcrumed thereon by means of the pin 13; this lever 12 carries thereon the finger 14 pivotally mounted at 15; the coupling head has the opening 16 therethrough for the reception of the finger 14, which is adapted to enter the coupling head and engage the knuckle tail 4 at an appropriate point preferably recessed as shown at 17; a bar or rod or chain or other preferred means as is well understood in this art, may be attached to lever 12 at 18, to extend across the end of the car to a point within reach of the operator, who is not therefore required to pass between the cars in manipulating the coupling, to open the same.

The operation of my improvements is as follows: Referring to Fig. 1, the parts are shown in locked position, the lower end of the locking pin 3 resting in contact with one arm of the lever 9, the other arm of said lever being thereby brought into contact with the side of the coupling head, and lever 12 being also in contact with the coupling head adjacent its outer end and the finger 14 being held in its outer position by engagement with the knuckle tail. To manipulate the parts, lever 12 is swung outwardly on the pivot 13, and as finger 14 is held from moving inwardly by the knuckle tail 4 which is locked against movement, the effect of

swinging lever 12 as described, is to cause lever 9 to swing upon its pivot 8, whereby locking pin 7 is lifted upwardly and sidewise to its lock-set position as shown in Fig. 2; 5 the knuckle being now unlocked, a further movement of lever 12 will cause the finger 14 to be forced against the knuckle tail, thereby swinging the knuckle on its pivot and opening the same. It is seen that the unlocking 10 and the opening of the knuckle is accomplished by moving the levers in one direction only, and that the manipulation of lever 9 is accomplished by the movement of lever 12. The lever 9 being overloaded, the levers are 15 returned by gravity to the position shown in Fig. 1 as soon as the outward pull thereon ceases; when the knuckle is closed, the locking pin 3 is released and through gravity descends to a position of rest upon a shoulder 20 formed appropriately within the head.

It will be seen that the manipulation of the locking pin and the knuckle is much more quickly and surely performed by means of my improved lever construction, and at the 25 same time a simple and efficient device is obtained.

While I have shown my improvements in combination with a coupler of the well known Janney type, yet I do not regard the 30 construction as confined to that type of coupler, and therefore do not limit myself in that respect; further modifications may be made in the construction and the mounting and operation of my improvements, 35 which fall within the spirit of my invention and I desire to claim all such modifications.

What I claim is:

1. In a coupler having a swinging knuckle and a locking device to secure the knuckle in 40 locked position, a lever fulcrumed to the outside of the coupler and constructed to move the locking device to its unlocked position, and a second lever fulcrumed upon said first lever, and constructed to be swung 45 thereon to actuate said first lever and also to open the knuckle.

2. In a coupler having a swinging knuckle and a locking device to secure the knuckle in 50 locked position, a lever fulcrumed to the outside of the coupler and constructed to move the locking device to its unlocked position, a second lever fulcrumed on said first lever, and constructed to be moved in one direction to actuate said first lever and also to open 55 the knuckle.

3. In a coupler having a swinging knuckle and a locking device therefor, a lever fulcrumed to the outside of the coupler, a sec-

ond lever fulcrumed thereon, a finger pivoted to said second lever and adapted to engage 60 said knuckle, said second lever being adapted to be moved in one direction to actuate said first lever to move said locking device to its lockset position whereupon a further movement of said second lever in the same direction forces said knuckle open.

4. In a coupler, a coupling head having an opening formed therein, and provided with a swinging knuckle and a locking device to secure the knuckle in locked position, a lever 70 fulcrumed to the outside of the coupler having its upper end bifurcated, a second lever pivoted thereon and adapted to swing within said bifurcated portion, a projection formed upon said second lever and adapted to enter 75 said opening, whereby a continuous pull upon said second lever causes said first lever to unlock said knuckle and the projection upon said second lever to push said knuckle open.

5. In a coupler, a coupling head provided with an opening therein, a swinging knuckle and a locking device to secure the knuckle in locked position, a lever fulcrumed to the outside of the coupler, arms formed upon 85 said lever, a second lever pivoted thereto to swing between said arms, a member formed upon said second lever to enter said opening, said levers being adapted to be operated by a continuous pull upon said second lever 90 whereby said first lever unlocks the knuckle and the member on said second lever pushes the knuckle open.

6. In a coupler, a coupling head provided with an opening therein, a swinging knuckle 95 and a locking device to secure the knuckle in locked position, a lever fulcrumed to the outside of the coupler, a second lever pivoted upon the upper end of said first lever, a member formed on said second lever and adapted 100 to enter said opening and engage the tail of said knuckle, whereby a continuous pull upon said second lever operates said first lever to lift the lock to its unlocked position, the fulcrum for this movement being formed by the 105 engagement of said projection with the knuckle tail, and a further pull in the same direction causes said member to swing said knuckle open.

In testimony whereof I affix my signature 110 in the presence of two witnesses.

JAMES TIMMS.
